Application April 12, 1950, Serial No. 155,476

31 Claims. (Cl. 209—241)

1

This invention relates to an apparatus for charging material into the top of a receptacle and, while not limited thereto, is particularly useful for charging material in the form of discrete bodies into a rectangular shaft furnace.

In certain material treatment processes it is desired that the material move downwardly through a treatment zone at a predetermined rate with each of the discrete bodies or units subjected to substantially the same conditions in the same length of time. For example, the formation of pellets or aggregates from fine ore, ore concentrates, or mixtures of finely divided metalliferous material with fuel and other substances, may be effected by forming such material or materials into discrete, substantially symmetrical bodies, such as balls, and then heating. This heating, when properly effected, will harden the pellets so that they may be handled by conventional ore handling equipment and form a suitable charge for a blast furnace or similar ore treatment apparatus. The heating must, however, be carefully controlled to prevent fusion of the discrete pellets or bodies into excessively large clusters. Consequently, all the pellets or bodies should be subjected to substantially the same temperatures for substantially the same periods of time.

In the copending U. S. patent application of John J. Craig et al., Ser. No. 71,512, filed January 18, 1949, there is disclosed a shaft furnace in which the above-mentioned heating of aggregates or pellets may be readily effected. In such a furnace the discharge of the hardened pellets or aggregates is effected at the bottom of the furnace at a substantially uniform rate throughout the cross-sectional area so that the individual pellets in any transverse plane move downwardly within the furnace at substantially the same rate, thereby insuring that each pellet or aggregate will be subjected to substantially the same amount of heat in its movement through the furnace. In such an installation, it is essential that the material being treated be charged into the top of the furnace at a substantially uniform rate throughout the cross-sectional area thereof and, moreover, provision should be made for filling any voids that may occur in the top surface of the material so that the depth thereof will remain substantially uniform throughout the furnace. Moreover, it is desirable that the individual pellets or bodies of the material all be of a size greater than a predetermined minimum value.

Similar requirements and problems are en-

5 countered with material receptacles other than shaft furnaces in which material is supplied to the top thereof, to replace that withdrawn from a point adjacent the bottom, and where it is desired to maintain a substantially uniform predetermined amount of material in the receptacle, with the individual bodies of the material having a size greater than a predetermined minimum. Consequently, while reference has been made and 10 will hereinafter be made to charging a shaft furnace with material in the form of discrete bodies, and while the present preferred embodiment of the invention is particularly designed for such a use, it is to be understood that the invention is not limited to charging a shaft furnace with pellets or discrete bodies of ore, ore concentrates or the like, but may be utilized wherever similar problems arise.

An object of the invention is to provide an improved apparatus for charging material, in the form of discrete bodies, into a receptacle, such as a shaft furnace or the like, the apparatus including means to separate bodies having a size less than a predetermined value from the material as it is conveyed towards the receptacle for charging thereto.

Another object of the invention is to provide an improved apparatus for charging material, in the form of discrete bodies, into a receptacle, such as a shaft furnace or the like, the apparatus including conveyor means for conducting the material from a source of supply to a classifying means which removes bodies of a size less than a predetermined minimum and delivers the remainder of the bodies to another conveying means which in turn deposits the bodies in the receptacle, the classifying means being so constructed and arranged that it delivers the material bodies to the last-mentioned conveyor means with a substantially uniform distribution transversely thereof, whereby only bodies of the material having a size greater than a predetermined minimum are charged into the receptacle and the charged material is distributed substantially uniformly therein.

50 A further object of the invention is to provide an apparatus for charging material into a receptacle, such as a shaft furnace or the like, from which material is removed adjacent the bottom thereof, the charging being effected by reciprocating conveyor means in a manner to provide and maintain the top surface of the material in the receptacle substantially level and at a substantially constant elevation.

An additional object of the invention is to

provide an apparatus of the type referred to in the preceding object and in which means are provided to selectively effect automatic reciprocation of the conveyor means or manual control thereof, thereby effecting charging of material in substantially uniform layers and facilitating filling of any voids which may occur in the top surface of the material within the receptacle.

A still further object of the invention is to provide an apparatus for charging material into the top of a receptacle, such as a shaft furnace or the like, with a substantially uniform distribution of the material throughout the cross-sectional area of the receptacle, which apparatus comprises conveyor means adapted to transport the material from a point of supply to the receptacle, means moving the delivery end of said conveyor means transversely over the said receptacle to distribute the material therein, indicating means having a portion movable transversely of the receptacle to detect the top level of the material therein, and manually operable means to vary the transverse movement of said conveyor means, whereby voids in the top surface of the material in the said receptacle are detected and filled.

An additional object of the invention is to provide an apparatus of the type mentioned wherein means are provided to screen the material while conveying the latter from a point of supply to the receptacle so that only bodies of the material having a size greater than a predetermined minimum are charged into the receptacle, the screen means being so constructed and actuated as to effect uniform distribution of the material transversely of the screen and of the conveyor means transporting the material from the screen to the receptacle being charged.

A more specific object of the invention is to provide an improved apparatus for charging material, in the form of discrete bodies, into the top of a receptacle from which material is removed adjacent the bottom thereof, the said apparatus comprising a power driven carriage reciprocable adjacent the top of the receptacle, screen means on said carriage to which the material is supplied, and conveyor means positioned to receive material passing over said screen means with the said conveyor means being connected with said carriage and reciprocated thereby over the receptacle being charged, there being power means for effecting automatic reciprocation of said carriage and operator actuated means to selectively control reciprocation whereby only bodies of the material having a size greater than a predetermined minimum are charged into the receptacle to replace those withdrawn from the bottom thereof with the charging being effected in a manner to maintain the top surface of the material in the receptacle substantially level and at a substantially constant elevation.

Another object of the invention is the provision of an apparatus as defined in the preceding object, which apparatus also includes feeler means reciprocated with said conveyor means over the surface of the material in the receptacle, the said feeler means being connected to signal means thereby enabling the operator to determine the nature of the top surface of material in the receptacle and to control reciprocation of said carriage, thus facilitating controlling the charging of said receptacle from a location remote from the latter.

A still more specific object of the invention is

the provision of an apparatus for charging material, in the form of discrete bodies into the top of a receptacle, such as a shaft furnace or the like, comprising a power driven carriage mounted for reciprocation adjacent the top of said receptacle, power driven screen means on said carriage and power driven conveyor means for conducting material to and from said screen means with the conveyor which conducts material from the screen means having its delivery end reciprocable over the top of said conveyor as the result of reciprocation of said carriage; and means controlling the several power means for operating said carriage, screen means and conveyor means to effect starting and stopping thereof in a predetermined sequential order.

The invention further resides in certain novel features of construction and combination and arrangements of parts, and further objects and advantages thereof will be apparent to those skilled in the art to which it pertains from the following description of the present preferred embodiment thereof, described with reference to the accompanying drawings, in which similar reference characters represent corresponding parts in the several views, and in which:

Fig. 1 is a side view of an apparatus constructed in accordance with this invention and adapted for charging a rectangular shaft furnace, the view being principally in elevation but certain parts being broken away and others shown in section;

Fig. 2 is a top plan view of the apparatus illustrated in Fig. 1 but removed from the furnace;

Fig. 3 is a longitudinal sectional view of the conveyor means of the apparatus which is reciprocated over the furnace or other receptacle being charged, the view being to an enlarged scale with respect to Figs. 1 and 2;

Fig. 4 is a top plan view of the conveyor means illustrated in Fig. 3 with portions of the conveyor belt removed to more clearly illustrate the construction;

Fig. 5 is a sectional view taken substantially on the section indicating line 5—5 of Fig. 3;

Fig. 6 is a longitudinal sectional view through the lower part of the movable carriage of the apparatus with certain parts broken away, the view illustrating the drive for the carriage and for the conveyor means provided to remove material passing through the screen means;

Fig. 7 is a top plan view of the apparatus illustrated in Fig. 6, a portion of the conveyor belt being removed to more clearly illustrate the construction;

Fig. 8 is a fragmentary sectional view, with parts broken away and others shown in elevation, illustrating the manner in which material is supplied to the apparatus, the view being taken substantially on the line 8—8 of Fig. 1;

Fig. 9 is an enlarged view, partly in section and partly in elevation, taken substantially on the line 9—9 of Fig. 1 and illustrating the feeler members of the indicating means;

Fig. 10 is an enlarged fragmentary view of one of the feeler means and the support therefor illustrated in Fig. 9;

Fig. 11 is a front elevational view of a main control panel for the apparatus;

Fig. 12 is a front elevational view of an auxiliary control panel for the apparatus;

Fig. 13 is a fragmentary detached view to an enlarged scale of one of the supports for the screen means;

Fig. 14 is a simplified, schematic electrical wiring diagram illustrating the energizing and control circuits for the motors and indicating means of the apparatus; and

Fig. 15 comprises a key to the wiring diagram of Fig. 14, the key being so arranged that when Figs. 14 and 15 are placed side by side, the relay coils and contacts in the key are horizontally aligned with the corresponding coils and contacts in the circuit diagram with the contacts actuated by each of the relay coils being vertically arranged in the key above and/or below the proper operating coil.

For the sake of simplicity and clarity of disclosure, the invention is illustrated as embodied in an apparatus for charging material in the form of discrete bodies into the top of a shaft furnace having a rectangular cross-section. The furnace per se forms no part of this invention and is fully illustrated and described in the aforementioned copending application Ser. No. 71,512, filed January 18, 1949. For the purposes of the present disclosure, it is sufficient to note that such a furnace, designated generally 20, constitutes a receptacle into which the material, in this case substantially symmetrical pellets or aggregates containing iron concentrates or the like, is charged at the top and moves downwardly therethrough, being finally discharged from the bottom thereof by means not shown.

The novel charging apparatus comprises a plurality of conveyor means carried by a reciprocating support or carriage 21 mounted for movement transversely relative to the top of the furnace 20. In the illustrated embodiment, the carriage 21 comprises a frame 22 formed from structural steel members 23, 24, 25 and 26 secured together by welding, riveting or the like, in a substantially rectangular configuration. This frame is preferably strengthened by suitable transverse members such as 27, 28 and 29 and by diagonal braces such as 30, 31, see Fig. 7. The carriage 21 is supported for reciprocating movement adjacent the top of the furnace 20 by flanged wheels 32, 33, 34, 35, 36 and 37 which run upon spaced rails, such as 38, 39, mounted upon a suitable supporting means and extending substantially at right angles from one side wall of the furnace. The pair of wheels 32, 37 are each keyed to an axle, such as 40, carried in suitable bearings such as 41 supported upon the longitudinal frame members 23 and 24. The driving wheels 33, 36 are each keyed to an axle 42, which is supported upon the frame members 23 and 24 in suitable bearings similar to 41.

The axle 42 for the wheels 33 and 36 has a portion thereof extending beyond one of the wheels, such as wheel 36, and this extending portion of the axle 42 is provided with a sprocket wheel 43. A chain 44 passes about the sprocket wheel 43 and about a sprocket 45 provided upon the drive shaft 46 of a change speed mechanism 47. This change speed mechanism is supported on a suitable platform or mounting plate on the carriage 21 and has its input connected with the armature shaft 48 of a reversible electric motor 49, which is also supported by a suitable mounting plate, or the like, upon the carriage 21. It will be apparent that rotation of the motor 49 in one direction effects movement of the carriage 21 towards the furnace 20, while energization of the motor 49 for rotation in the reverse direction moves the carriage in the opposite direction.

As will hereinafter appear, the carriage is normally continuously reciprocated, this being

effected by automatic reversals of the direction of energization of the motor 49 when the carriage is adjacent the limiting positions of movement thereof. For this purpose electrical switches 50 and 51 are supported for engagement by actuating members 52 and 53 at spaced points upon the frame member 23 of the carriage 21, see Figs. 1 and 6. The switches 50 and 51 are mounted on or adjacent to the rail 38 and are so positioned that the switch 50 is engaged by the actuating member 52 when the carriage 21 has reached the position illustrated in Figs. 1 and 6, which for convenience is termed the forward position. The switch 51 is so located as to be engaged by the actuating member 53 when the carriage has reached its other extreme position, which for convenience is called its rear position. The switches 50 and 51 are connected in the control circuit for the motor 49, as hereinafter described, in a manner controlling reversal of the energization thereof. In addition to the switches 50, 51, a switch 54 is supported in a manner to be capable of engagement by the actuating member 53 when the carriage is moved beyond its normal rearward-most extent of travel. The switch 54 is provided for the purpose of preventing overtravel when the carriage is being moved rearwardly sufficiently to completely remove the forward conveyor from the furnace hood.

The longitudinal members 23 and 24 of the frame are each provided with spaced vertically upwardly extending supports or standards 55 and 56 upon which an intermediate support 57 for a material classifying or screen means 58 is mounted. Preferably the support 57 is bolted to the standards 55 and 56 so that shims may be inserted to adjust the level of the material classifying means and thereby ensure uniform lateral distribution of the material thereover. The material classifying means 58, here illustrated as including a slotted plate portion 59, a pivoted plate or gate 60, and a screen portion 61, is supported at an angle and is subjected to vibratory movement to move the material thereover. Preferably, the motion imparted to the pellets on the classifying means 58 is such as to cause them to travel in small arcs towards the lower end to thereby prevent lodgment of the pellets in the openings of the slotted portion 59 or of the screen portion 61. The pivoted plate 60 is provided to permit diversion of the material from its path over the screen if it be desired to prevent a portion of the material from reaching the furnace, a handle 60a being connected to the plate 61 to move the latter. For the sake of brevity the classifying means will be hereinafter referred to simply as a screen or screen means. Hence the subsequent use of these terms, unless otherwise indicated, is intended to refer to the entire classifying means and not simply the portion 61 thereof.

As shown in Figs. 1 and 13, the support 57 is provided with spaced brackets 62 arranged in pairs on opposite sides of the classifier means 58 adjacent the ends thereof. Each bracket is provided with bearing supports 63 in which a grooved wheel 64 is journaled. The frame 65 of the screen means 58 is provided with brackets 66 substantially aligned with the brackets 62. The brackets 66 support plates 67, the lower surfaces of which are provided with V-shaped flanges 68 received in the grooves of the wheel 64. Preferably the plates 67 are tiltable with respect to the brackets 66 to thereby alter the nature of the vibratory motion imparted to the screen means.

In the embodiment shown, the plates 67 are pivoted to bolts 69 secured to the brackets 66 and one or more plates or wedges 70 are inserted between the plates 67 and the frame 65. Hence, when a thrust is applied to the frame 65, the plates 67 tend to ride up the wheels 64 imparting both a forward and upward motion to the material upon the screen, the extent of which motion may be altered by varying the inclination of the plates 67. The material is thus fed forward and is simultaneously screened, the smaller particles falling through the openings of the plate 59 or of the screen 61.

The classifying means or screen means 58 is moved or vibrated by a suitable mechanism 71. In the illustrated embodiment the mechanism shown is of the type "Deister Concenco" head motion or mechanism and comprises an eccentric on a rotatable shaft connected to the screen means 58, by suitable links and a coiled spring, for imparting oscillatory movement to the screen means, the shaft of the mechanism 71 being driven by an electric motor 72. The mechanism 71 and motor 72 are mounted upon a supporting frame 73 secured to and extending rearwardly from the support 57. This support is preferably weighted or loaded to prevent undesired vibrations from being transmitted to the frame 22 of the carriage. Preferably the width of the classifying means or screen 58 is substantially the same as the width of the furnace, or other receptacle, to be charged and the sides of the frame 65 are provided with upstanding guard rails or flanges to prevent the material from dropping over the sides of the screen. The rate of feeding the material over the screen may be adjusted both by varying the inclination of the plates 67 and by varying the speed of the motor 72. Uniformity of distribution of the material transversely of the screen is effected by inserting shims or wedges between the posts or standards 55, 56 and the support 57.

It will be apparent that any material placed adjacent the upper end of the screen means 58, the right-hand end as viewed in the drawings, will feed downwardly thereover and be discharged from the lower end thereof. During this passage of the material over the screen, any bodies of the material having their greatest dimension smaller than the openings in the screen will drop therethrough so that only bodies or pellets of greater than predetermined size, which size is determined by the mesh of the screen, can be fed to the furnace, or other receptacle. The material which drops through the screen, due to its small size, is directed by means of a chute 74 onto a belt conveyor 75 which is supported upon the carriage 21 and has the top flight thereof moving in a direction from left to right as viewed in Fig. 1.

As shown in Figs. 6 and 7, the belt 75 is driven by means of an electric motor 76 supported upon the frame 22 of the carriage 21 and driving a sprocket 77 through a speed change unit 78. The sprocket 77 is connected by means of a chain 79 with a sprocket wheel 80, which is in turn keyed or otherwise secured to the axle 81 of the driving drum 82 for the belt 75, this belt drum 82 being supported by suitable bearings, such as 83, upon the frame 22. Adjacent the opposite end of the frame 22 is an idler belt drum 84 about which the conveyor belt 75 passes, this drum 84 having its bearings adjustably secured to the frame 22 so that the said drum 84 may be moved longitudinally relative to the frame 22 by means of adjusting screws, such as 85, in a well known man-

ner to take up slack in the belt 75. The belt 75 is supported intermediate the drums 82 and 84 by idler rollers, such as 86 and 87, extending transversely of the frame 22 below the upper flight of the belt 75, and by a roller 88 likewise supported upon the frame 22 and extending below the lower flight of the belt.

Material passing through the screen 58 is, as mentioned above, directed by the chute 74 onto the conveyor belt 75 and the latter moves this material towards the right-hand end of the carriage 21, as viewed in the drawings, the material being discharged therefrom through a chute 89 which is supported intermediate the tracks 38, 39 on which the carriage 21 runs. This chute 89 is normally stationary and therefore has a length such that the delivery end of the conveyor 75 is at all times over a portion of the chute 89 regardless of the position of the carriage 21 in its reciprocatory path. Material discharged through the chute 89 is received upon a suitable belt conveyor 90 and is carried by the belt conveyor to a suitable place of discharge. Where, as in the described embodiment of the invention, the material handled is raw or unheated pellets of iron ore agglomerates, the material passing through the screen and carried away by the conveyors 75 and 90 may be returned to the pelletizing apparatus for recirculation therethrough or may be otherwise disposed of as may seem expedient at the time. A chute or shield 91 is supported upon the frame 22 of the carriage adjacent the discharge end of the conveyor belt 75 to guide the material from the belt into the chute 89 and prevent such material from being thrown upon the portion of the frame on which the electrical motors 49 and 76, together with the change speed units 47 and 78, are supported.

The material passing from the delivery end of the screen 58 is delivered into the furnace 20 by a conveyor means, generally designated 92. This conveyor means comprises a framework 93 formed of suitable structural members welded or riveted together, with one end connected to the portion of the frame 22 for the carriage 21 adjacent the delivery end of the screen 58. The frame 93 is provided, adjacent its ends, with transversely extending axles 94, 95 on which are mounted pairs of flanged wheels 96 and 97, respectively, adapted to run upon rails, such as 98 and 99, see Fig. 9, supported adjacent the top of the furnace 20 and at either side thereof. The rails 98 and 99 are parallel with the previously mentioned rails 38 and 39 so that the conveyor means 92 is reciprocated in a straight line when the carriage 21 is reciprocated by operation of its motor 49. Movable supported upon the frame 93 of the conveyor means 92 is a suitable conveyor belt 100, which in the present instance is shown as formed of woven wire or other heat resistant material. This conveyor belt 100 may, however, be formed of fabric, rubber, or mixtures thereof when the temperature at the top of the receptacle or furnace 20 is not high enough to damage such materials.

The conveyor belt 100 is adapted to be driven by a motor 101 which is suspended below the frame 93 adjacent the connection of the latter to the carriage 21. This motor 101 drives a sprocket 102 through a change speed unit 103, the sprocket 102 being connected by a chain 104 to a sprocket wheel 105, which is keyed or otherwise connected with an axle 106. The axle 106 is provided with a driving drum 107 for the conveyor belt 100 which passes therearound

and around an idler drum 108 adjustably supported upon the frame 93 adjacent the other end thereof. Adjustment of the position of the drum 108, and hence of the amount of slack in the conveyor belt 100, is effected by means of screws, such as 109, in the conventional manner clearly apparent from an inspection of Fig. 4.

Due to the fact that the belt 100 is formed of wire mesh, woven wire, or the like, and because it is to support pellets of iron ore agglomerates, the combined weight of the belt and its material is relatively high. Moreover, since it is desired that there be no substantial troughing action of this belt, in order that the pellets will remain uniformly distributed thereover until deposited in the furnace, the upper flight of the belt is supported upon a plurality of idler rollers 110 and 111 which extend angularly towards each other in a herringbone pattern, see Fig. 4. As shown therein, one end of each of the rollers 110, 111 is journaled in a bracket such as 112, 113, respectively, supported upon opposite sides of the frame 93, the adjacent ends of the rollers 110, 111 being supported in brackets 114 and 115, respectively, located substantially medially of the frame 93 upon a suitable longitudinally extending portion 116 thereof. The lower or return flight of the belt, since it does not carry the weight of material being charged may be supported upon a relatively few idler rollers, such as 117, which extend transversely of the conveyor belt 100 in the conventional manner. A slack takeup adjustment for the belt is shown as comprising a pair of idler rollers 118, 119 mounted on opposite sides of the lower flight of the conveyor belt and supported at their opposite ends by links or bars such as 120 and 121, these bars being pivoted to the frame 93 as indicated at 122 and 123. It will be apparent that the tension of the belt 100 may be readily adjusted by altering the angularity of the bars 120 and 121 which may be secured in an adjusted position in a conventional manner.

The width of the conveyor belt 100 is substantially equal to the width of the opening at the top of the shaft furnace 20, or other receptacle to which the material is delivered, and the length of distance through which the delivery end of the belt 100 is moved is substantially equal to the other transverse dimension of the opening at the top of the shaft furnace or other receptacle. Consequently, the pellets, or other material, are deposited in the furnace, or other receptacle, as substantially uniform layers across the entire cross section thereof when the conveyor belt 100 is driven and reciprocated. In order to prevent excessive piling up of the material adjacent the left-hand and right-hand side walls of the furnace, as viewed in the drawings, when the conveyor reverses its direction of movement, the length of reciprocating stroke of the conveyor is preferably made slightly less than the actual transverse dimension of the furnace or other receptacle in this direction, so that the delivery end of the conveyor belt stops in its reciprocatory movement somewhat short of the inner faces of these walls of the furnace or receptacle 20. This is desirable because, during the change of direction of reciprocation, the delivery end of the conveyor will be over a given area of the furnace 20 or other receptacle adjacent the said side walls for a longer period of time than it is over an area of corresponding size intermediate these side walls, as for example, adjacent the center of the receptacle.

By the mechanism thus far described, it will be apparent that the material supplied to the upper end of the screen or classifying means 58 will be delivered with a substantially uniform distribution over the discharge end of the conveyor belt 100 so as to form successive layers of material within the receptacle or furnace 20 of substantially uniform thickness throughout the cross-sectional area thereof. This theoretical distribution of the material is not, however, likely to be achieved at all times during the normal automatic operation of the apparatus, this being due, for example, to the manner in which the material is withdrawn from the bottom of the furnace, and perhaps to other causes. In any event, it is essential that no appreciable voids occur in the upper surface or the top level of material within the furnace 20 since this would change the relative amount of heat to which the particles in the various parts of the furnace were subjected. Therefore, an indicating means is provided by which the top surface or stock level of the material within the receptacle or furnace 20 may be detected, and provision is also made for manually interrupting or otherwise controlling the cycle of reciprocation of the conveyor 100 so that, when detected, voids or irregularities in the surface of the material in the furnace 20 can be readily corrected. The indicating means may take a variety of different forms but, in the present preferred embodiment, comprises a plurality of feeler means which are adapted to be reciprocated transversely of the receptacle over the top surface of the material therein and to indicate the presence of the material by contact therewith.

As will be seen from Figs. 1, 3, 9 and 10, the feeler members of this indicating means, in the present embodiment, comprises a plurality of metal chains 124. These chains are preferably each individually supported upon an insulating spool or member 125, the spools being supported upon axles such as 126 mounted in and carried by separate, substantially U-shaped, brackets 127 which are welded or otherwise secured to the under side of a transversely extending member 128. The member 128 is preferably supported in an inclined position adjacent the discharge end of the conveyor 100, as will be seen from Fig. 3, by downwardly extending arms or brackets such as 129 carried by a transversely extending member 130 secured to the frame 93 of the conveyor 100. By this construction the transversely extending member 128 forms a shield preventing pellets or other bodies of material, which are discharged from the belt 100, from striking or otherwise directly contacting the chains 124 as well as providing a support for the latter. The transverse member 128 also aids in spreading or directing the flow of the pellets discharging from the end of the conveyor 100.

Each of the chains 124 is provided with a connection 131 to an electrical cable or conductor 132 leading to a suitable control panel or panels having signal lights which are adapted to be illuminated only when the corresponding chain 124 engages pellets within the furnace 20, as will be hereinafter described. Since the conveyor 100 is normally automatically reciprocated over the top of the furnace 20, it will be apparent that the chains 124 continuously move back and forth over the surface of the material in the furnace. Whenever one of the chains contacts a portion of the material in the furnace, a circuit is closed

lighting the corresponding signal light whereupon the operator may terminate the feeding of material, as hereinafter described, until the signal light is extinguished. Preferably, however, the carriage will be allowed to operate continuously so long as all the signal lights are illuminated and manual control of movement of the carriage and of the feeding of the material will be invoked only when one or more of the signal lights is extinguished to thereby effect filling of a void in the top layer or the surface of the material which is thus indicated.

In addition to the above mentioned conveyors and screen means, the carriage 21 is also provided, adjacent the end thereof opposite that carrying the conveyor 160, with upwardly extending support members, such as 133, which carry a conveyor frame 134 at the top thereof, the latter being further supported or braced by diagonally extending members such as 135. The conveyor frame 134 is provided with a suitable conveyor belt 136 which is driven by an electric motor 137 through a suitable speed change unit 138, see Fig. 8. The conveyor belt 136 is of substantially conventional construction and hence need not be described in detail. Suffice it to note that the upper flight of the belt is supported upon suitable idler rollers 139 and the end of the frame 134, adjacent the screen or classifier 58, has a downwardly inclined portion 140 in which is supported the forward or idler drum 141 for the conveyor belt 136 so that this portion of the conveyor is closely adjacent the upper end of the vibrating screen. The lower flight of the conveyor belt 136 is supported by suitable idler rollers 142 and shields or guards 143 are provided adjacent the opposite sides of the belt 136 to prevent displacement of the material therefrom. The relationship of these guards or shields 143 and their manner of support upon the frame 134 will be readily apparent from Figs. 1 and 8 and hence need not be described in detail.

The material is brought to the reciprocating carriage and the conveyor means thereof from a source of supply, such as a balling drum or the like, not shown, by suitable conveying means adapted to deliver the material to the conveyor 136 at all times during reciprocation of the carriage 21. For this purpose the apparatus preferably includes a power driven conveyor belt 144, see Fig. 8, the delivery end of which is mounted adjacent the upper flight of the belt 136, the belt 144 being driven by a motor 145 operating through a change speed mechanism 146. Preferably a delivery chute 147 is supported upon stationary means, not shown, adjacent the end of the belt 144 so that the material delivering therefrom is deposited upon the belt 136 as the latter reciprocates therebeneath during the operation of the carriage 21, the forward position of the carriage being indicated in full lines in Fig. 1 with the position of the conveyor 144 indicated in broken lines thereabove. The rearwardmost position of the carriage 21 is indicated in broken lines in Fig. 1 and for this position of the carriage 21 the conveyor 136 thereof will have moved so that the chute 147 and conveyor 144 are adjacent the inclined portion of the conveyor 136. As a positive means of stopping and preventing overtravel of the carriage 21 in either direction the rails 38 and 39 are preferably provided with arcuate stop blocks or wheel clogs 148, 149.

The motor 49 for the carriage 21 is preferably of the direct current, compound wound, reversi-

ble type. The motors 76, 101, 137 and 145 for the conveyors 75, 100, 136 and 144, respectively, are also preferably of the direct current, compound wound type, but need not be, and preferably are not, reversible. The motor 72 for the screen means 58, however, is preferably of the three-phase, alternating current type. In normal operation, these motors and the indicating means for detecting the top surface or stock line of the material in the furnace 20 or other receptacle are energized and deenergized in a predetermined sequence to insure proper movement of the material being charged and to prevent piling up of the material in any one part of the feeding apparatus. The order of starting is: first, energization of the indicating means and of the carriage motor 49 with sequential energization of motors 101, 76, 72, 137 and 145 in that order after the motor 49 is energized. Stopping of the motors is effected in the same order and stopping of any motor stops all other motors preceding it in the said sequential order. In addition to this sequential control, provision is made for temporarily stopping the carriage reciprocating motor 49 without interrupting energization of the other motors. Means are also provided to permit manual reversal of the motor 49 independently of the position of the carriage relative to the switches 50 and 51 which control automatic reversal thereof. In addition means are provided to permit individual manual control of the operation of the indicating means and of each of the motors, this manual control being for the purpose of setting up, trial operations, and the like.

The manually operable switches, and the relays controlling the operations of the motors and of the indicating means are schematically illustrated in the simplified wiring diagram comprising Fig. 14, it being understood that conventional devices such as current limiting resistances, overload devices, fuses and the like have been omitted for the sake of simplicity. The relationship of the operating coils of the relays and the contacts operated by each of these coils will be apparent from the key diagram comprising Fig. 15 which is so constructed that, when placed side by side with Fig. 14, the coils and contacts shown in the two figures and bearing like reference numerals are in horizontal alignment while all contacts operated by a given relay coil are shown in Fig. 15 in vertical alignment with each other and with its operating coil.

Referring now to Fig. 14, it will be seen that power is supplied to the circuit through power supply lines L1, L2 and L3 which are connected to a source of electrical energy of the three-phase, alternating current type. The power lines L1, L2 and L3 are connectible to the wires 150, 151 and 152 of the circuit for the apparatus through a disconnect switch 153. Connected to the wires 150, 151 and 152 is a three-phase alternating current motor 154 which has its shaft operatively connected to drive a direct current generator 155, the output wires 156 and 157 of the latter being connectible to wires or bus bars 158 and 159 by means of a disconnect switch 160.

The wires or bus bars 158 and 159 supply direct current electrical energy for both the control and the energizing circuits of the motors 49, 76, 101, 137 and 145. Thus, the wire or bus bar 158 is connected with a wire or bus bar 161 forming one main power lead for the control circuits of these motors, the wire or bus bar 159 being connected with wire or bus bar 162 form-

ing the main power line of opposite polarity for the control circuit. Likewise, the wire or bus bar 158 is connected with the main supply bus bar or wire 163 of the energizing circuit for the said motors while the wire or bus bar 159 is connected with the wire or bus bar 164 constituting the other main power supply line for the energizing circuit of these motors.

The control circuit for governing energization of the motor 72 and of the indicating means is preferably operated by alternating current. Consequently, two of the main power supply lines, such as 150, 152, are connectible to the primary 165 of a step-down transformer through a disconnect switch 166. The secondary 167 of this transformer has its terminals connected with the power supply lines or bus bars 168 and 169 for the control circuit of motor 72 and of the indicating means. Energizing current of the alternating type for the motor 72 is supplied from the wires 150, 151, 152 through a disconnect switch 170 and relay controlled contacts as hereinafter described. The indicating means are energized by alternating current from the wires 150 and 152 as will hereinafter be apparent.

It is believed that the electrical circuit of the apparatus can best be understood from a description of the operation of the device as a whole. Let it be assumed that the feeding apparatus has been initially adjusted for proper operation and is therefore ready to begin automatic operation in transporting material, such as pellets or the like, from a suitable source of supply, and disposing or charging the same into the top of the receptacle such as the shaft furnace 20. The operator will initially close the previously mentioned switches 153, 160, 166 and 170 and also the manually operable disconnect switches 171, 172, 173, 174, 175, 176, 177, 178, 179, 180 and 181 in the motor energizing circuits. He then moves the blade of a selector switch 182, in the control portion of the circuit, to the position designated "Sequence." This setting of the selector switch closes a circuit from the wire 161 to the wire 183. At this time, however, the manually operable group start, push button switch 184 is in its open position, as shown in Fig. 14, so that while the circuit is prepared for proper operation, no operation begins at that time.

When, however, the operator now actuates the group start switch 184, the circuit is closed therethrough and through the coils 1CS and 2CS of the sequence controlling relays to the power line 162. Therefore, the coils 1CS and 2CS of these relays are energized closing their contacts 1CS1, 1CS2, 1CS3, 1CS4, 1CS5 and 2CS1, 2CS2, respectively. Energization of the relay 1CS also opens its normally closed contacts 1CS6. Closing the contacts 1CS1 completes a circuit controlling motor 49 of the carriage 21, the circuit extending from the wire 161 through the normally closed push button stop switches 185 and 186 to and through the said contacts 1CS1, thence through push button switch 187, the contact 188a of the manually operable switch 188 for controlling movement of the carriage, and through contact 189a of the push button switch 189 for manually initiating forward motion of the carriage, the circuit being completed to the wire 162 through the coil of a relay 1CR.

Energization of the relay 1CR closes its contacts 1CR1, thereby providing a holding circuit around the contacts 1CS1 so that when the but-

ton 184 is released relay 1CR remains energized. Energization of the relay 1CR also closes its normally open contacts 1CR2 thereby completing a circuit through these contacts and a wire 190 to and through the normally closed push button switch 191 for effecting reversal of the carriage, through the normally closed forward limit switch 50, and through the normally closed contacts 1R1 of a relay 1R, the circuit continuing to and through relay coils 1F and 2F to the wire 162 thereby energizing relays 1F and 2F. The energization of relay 1F closes its contacts 1F1 and 1F3 and opens its normally closed contacts 1F2. Opening of the latter contacts prevents improper energization of the relays controlling reverse movement of the carriage when the contacts 1CS6 close as a result of release of group start button 184. Closing of the contacts 1F4 completes a circuit through a normally closed manually operable push button switch 192 to and through the coil of a relay 1M to the power line 162 thereby energizing this relay. The energization of relay 2F causes closing of contacts 2F1 and the energization of relay 1M effects closing of its contacts 1M1 and 1M2.

The energization of relays 1F, 2F and 1M completes the energizing circuit for the carriage motor 49 to effect rotation of the latter in the direction which causes the carriage to move in its above mentioned forward direction. This will be apparent from an inspection of the right-hand side of Fig. 14 from which it is seen that the closing of the manually operable switches 171 and 172, in the initial setup of the apparatus, has prepared a circuit for the motor 49, this circuit now being completed through switch 171, the now closed contacts 1F3, the armature 49a of the motor 49, to and through the now closed contacts 2F1 and the series field winding 49b of the motor, the other side of this field winding being connected through the now closed contacts 1M1 and the switch 172 to the wire 164. It will be evident therefore that the operation of relays 1F, 2F and 1M has energized the armature 49a of motor 49. At the same time, the closing of contacts 1M2, as the result of energization of the relay 1M, has completed a circuit therethrough from the wire 161 to and through the coil of a relay DB to a wire 193 which is connected through a wire 194 with the wire 162. The resulting energization of the relay DB opens its contacts DB1 thereby removing a braking resistance 195 from the parallel circuit about the armature 49a. The initial closing of the switches 171 and 172 completed a circuit extending from switch 171 through a manually adjustable rheostat 196 and the shunt field 49c of the motor to the switch 172. Therefore the motor 49 rotates at a speed as determined by the adjustment of the rheostat 196 and in a direction moving the carriage 21 to the left as viewed in the drawings.

Simultaneously with, or slightly before, energization of the carriage motor, the stock level indicating means is energized by virtue of the closing of the contacts 2CS2 in response to energization of the relay 2CS. This completes a circuit from the wire 168 through the manually operable, normally closed, push button switches 197 and 198, the now closed contacts 2CS2 to and through the coil of a relay 2M, the circuit being completed from the latter coil to the wire 169. The resulting energization of relay 2M causes it to close its contacts 2M1, 2M2, 2M3 and

2M4. Closing of the contacts 2M1 provides a holding circuit about the contacts 2CS2 thereby maintaining the relay 2M energized after the manually operable switch 184 has been released with consequent deenergization of relay 2CS and opening of contacts 2CS2.

Closing of the contacts 2M2 and 2M3 completes a circuit energizing the indicating means. Thus, as will be seen from the upper right-hand portion of Fig. 14, the primary 199 of a transformer for the indicating means is connected to the wires 150 and 152 while the secondary 200 thereof is connected through the previously closed manually operable switch 173 to one side each of the normally open contacts 2M2 and 2M3. The other side of the contacts 2M2 is connected with a wire 201 which is in turn connected to one terminal each of a plurality of pairs of indicating lamps 202, 203, the other terminals of which are connected with the feeler means or chains 124. The contacts 2M3 are connected by suitable conductive means so as to be in conductive relationship with the material P within the furnace. This may be effected, for example, by connecting a wire 204 between the contacts 2M3 and a metallic portion of the furnace so that the circuit is completed through the latter to the material M therein, which in the present instance is electrically conductive, being pellets or agglomerates of iron ore or the like.

As shown in Figs. such as 9 and 14, the indicating means comprise four of the spaced chains 124, the lower ends of which are adapted to contact the upper surface of the material P, the upper ends of each of the chains being connected by the wires 132 to corresponding terminals of a pair of the indicating lamps 202, 203, the other terminals of which are connected with the wire 201. The several lamps 202, 203, which are preferably red, are identical but are located at different control stations, all of the lamps 202 being at one control station while all of the lamps 203 are at the other station. Hence, when the relay 2M is energized, as just described, the lamps 202, 203 associated with any chain 124 which contacts the upper surface of the material, such as pellets P, are illuminated. The lamps associated with the chains 124 which are out of contact with the material are not, however, illuminated. It is therefore possible to easily determine at a glance whether or not there are voids in the upper surface of the furnace or other receptacle, it being remembered that the chains 124 are continuously reciprocated back and forth over the surface of the material in the receptacle due to movement of the carriage.

Signal means are preferably provided to permit determining from a remote point whether or not the carriage is in operation and the indicating means energized. For this purpose, one or more red lamps, such as 205 and 206, may be placed at different points about the plant in which the apparatus is located, these lamps being lighted when the carriage is in operation due to the closing of the contacts 1CR4 in the control circuit as a result of energization of relay 1CR. At the same time, similarly located green lamps 207 and 208 will be extinguished by corresponding opening of the normally closed contacts 1CR5. When the carriage is not in operation, relay 1CR is deenergized so that the green lamps 207 and 208 are lighted and the red lamps 205 and 206 are extinguished. Likewise, red lamps 209 and 210 are controlled by the contacts 2M4 of relay 2M and green lamps 211 and 212 are controlled

by the contacts 2M5 of relay 2M. Hence, when the stock level indicating means is energized, the red lamps 209 and 210 are lighted due to closing of contacts 2M4 and at the same time the green lamps 211 and 212 are extinguished due to opening of the normally closed contact 2M5. When the stock level indicating means is deenergized, however, lamps 209 and 210 are extinguished and lamps 211 and 212 are lighted.

The previously mentioned closing of the contacts 1CS2 has completed a circuit from the wire 161 through the manually operable, normally closed, stop switch 213 to and through the contacts 1CS2, contact 214a of a push button switch 214, thence to and through the coil of a relay 2CR to the wire 162. Hence, the relay 2CR is energized and closes its normally open contacts 2CR1 and 2CR2. The closing of the contacts 2CR1 completes a circuit therethrough and through contacts 1CR6 of relay 1CR, which were closed in response to the previous energization of relay 1CR, to and through a relay 3M to the wire 162. The resulting energization of relay 3M closes its normally open contacts 3M1 and 3M2. Closing of the contacts 3M1 completes a circuit through the now closed contacts 2CR2 and 3M1 in parallel about the contacts 1CS2 so that the relays 2CR and 3M remain energized when the contacts 1CS2 open in response to deenergization of relay 1CS when push button 184 is released. The closing of the contacts 3M2 energizes the motor 101 since the manually operable switches 174 and 175 were closed in the initial setup of the machine, this energizing circuit extending from wire 163 through the switch 174, contacts 3M2, the armature 101a, the series field coil 101b and the switch 175 to the wire 164. The closing of the switches 174 and 175 also provided a circuit through the shunt field coil 101c and the adjustable rheostat 215 in series therewith. This places the conveyor 100 in operation which is evidenced by lighting of the red lamp 216 and extinguishing of the green lamp 217 due to the simultaneous closing and opening, respectively, of the contacts 2CR3 and 2CR4 of the relay 2CR in the control circuit.

The previously mentioned closing of contacts 1CS3 of the sequence control relay 1CS has completed a circuit from the wire 161 through a normally closed, push button, stop switch 218 to and through the said contacts 1CS3 and thence through the normally closed contact 219a of push button switch 219, the circuit extending through the coil of relay 3CR to the wire 162. The relay 3CR is therefore energized, thereby closing its normally open contacts 3CR1, 3CR2 and 3CR3 and at the same time opening the normally closed contacts 3CR4. Closing of the contacts 3CR1 now completes a circuit through the coil of relay 4M, this circuit extending from the wire 161 through the push button switch 218, the now closed contacts 3CR1, the contacts 2CR5 of the relay 2CR, which were closed when relay 2CR was energized, to and through the coil of relay 4M to the wire 162. The resulting energization of the relay 4M closes its contacts 4M1 and 4M2. Closing of the contacts 4M1 completes a parallel circuit about the contacts 1CS3 due to the previously mentioned closing of contacts 3CR2 by the energization of relay 3CR. Hence, the relays 3CR and 4M remain energized after the contacts 1CS3 open as the result of release of the push button 184. Closing of the contacts 4M2 energizes the motor 76 for effecting driving of the conveyor 75 since the manually operable

switches 176 and 177 in the motor circuit were closed in the initial setup of the machine. This energizing circuit for the motor 76, as shown at the right of Fig. 14, extends from the wire 163 through the switch 176, contacts 4M2, the armature 76a of the motor, the series field 76b of the motor and switch 177 to the wire 164, the shunt field 76c and the rheostat 229 for the motor 76 having been energized by the closing of the switches 176 and 177 during the initial setup. The fact that the motor 76 is in operation is indicated at the control stations since closing of the contacts 3CR3 has energized the red signal lamp 221 while opening of the contacts 3CR4 has de-energized the green signal lamp 222.

The closing of the contacts 2CS1, see the upper lefthand portion of Fig. 14, of the sequence control relay 2CS completed a circuit from the wire 168 through the normally closed, manually operable, push button switch 223 and through the now closed contacts 2CS1, to and through the normally closed contact 224a of a push button switch 224, the circuit continuing to the wire 169 through the coil of a relay 4CR. The resulting energization of relay 4CR causes the latter to close its normally open contacts 4CR1, 4CR2, 4CR3, 4CR5 and open its normally closed contacts 4CR4. The previously mentioned energization of the relay 3CR in the control circuit for motor 18 of conveyor 15 has also closed its contacts 3CR5. Hence a circuit is now completed from the wire 168 through the switch 223 and the now closed contacts 4CR1 and 3CR5 to and through the coil of a relay 5M to the wire 169. This energizes relay 5M causing it to close its normally open contacts 5M1, 5M2, 5M3, and 5M4. The closing of the contacts 5M1 completes a circuit through the now closed contacts 4CR2 and 5M1, which are in parallel with the contacts 2CS1, thereby providing a holding circuit for relay 4CR maintaining it energized after the contacts 2CS1 open when the relay 2CS is deenergized as the result of release of the push button 184. The closing of the contacts 5M2, 5M3, and 5M4 effects energization of the motor 72 for shaking the screen means 58 since the manually operable switch 170 was closed in initially setting up the apparatus for operation. The closing of the contacts 4CR3 has energized the red signal lamp 225 while the opening of the contacts 4CR4 has deenergized the green lamp 226, thereby indicating that the screen means 58 is now in operation.

The energization of the sequence control relay 1CS and the consequent closing of its contacts 1CS4 has completed a circuit from the wire 161 through the manually operable push button switch 227 to and through the said contacts 1CS4, and thence through the normally closed contact 228a of a push button switch 228, to and through the coil of a relay 5CR to the wire 162. The resulting energization of the relay 5CR closes its normally open contacts 5CR1, 5CR2, 5CR3, 5CR5 and opens its normally closed contacts 5CR4. Closing of the contacts 5CR1 closes a circuit from the wire 161 through the switch 227, contacts 5CR1 and the now closed contacts 4CR5, which were closed by the previous energization of relay 4CR in the control circuit for the screen motor 72, to and through the coil of a relay 6M to the wire 162. The energization of the relay 6M closes its normally open contacts 6M1 and 6M2. Closing of the contacts 6M1 completes a circuit therethrough and through the now closed contacts 5CR2, thereby providing a holding cir-

cuit for relay 5CR maintaining the latter energized after the contacts 1CS4 open upon de-energization of relay 1CS when the push button switch 184 is released. Closing of the contacts 6M2 completes a circuit energizing the motor 137 for the conveyor 136, it being remembered that the manually operable switches 173 and 179 are initially closed in the initial setup of the apparatus thereby completing a circuit through the shunt field 137c and the control rheostat 229. Hence, the closing of the contacts 6M2 now completes the circuit through the armature 137a and the series field 137b. The closing of the contacts 5CR3 has energized the red signal lamp 230 while the opening of the contacts 5CR4 has de-energized the green signal lamp 231 thereby indicating that the conveyor 136 is now in operation.

The conveyor 144 is started last in the automatic sequence under control of the sequence control relay 1CS and the previously mentioned energization of the relay 5CR. Thus, the closing of the contact 1CS5 completed a circuit from the wire 161 through the normally closed push button switch 232, the contacts 1CS5, the normally closed contacts 233a of a manually operable push button switch 233, to and through the coil of a relay 6CR to the wire 162. Energization of the relay 6CR closes its normally open contacts 6CR1, 6CR2, 6CR3 and opens its normally closed contacts 6CR4. The closing of the contacts 6CR1 completes a circuit from wire 161 through the switch 232, now closed contacts 6CR1 and 5CR5, the latter having been closed by the energization of relay 5CR when the conveyor motor 137 was energized, the circuit being completed through the coil of a relay 7M to the wire 162. The resulting energization of relay 7M closes its contacts 7M1 and 7M2. Closing of the contact 7M1 completes a circuit through these contacts and the now closed contacts 6CR2 in parallel with the contacts 1CS5 providing a holding circuit for the relay 6CR maintaining the latter energized after the contacts 1CS5 open upon deenergization of relay 1CS when the push button switch 184 is released. Closing of the contacts 7M2 energizes the motor 145 for the conveyor 144 by completing a circuit therethrough for the armature 145a and series field 145b since the manually operable switches 180 and 181 were closed in the initial setup of the apparatus. The closing of the switches 180 and 181 energized the shunt field 145c for the motor through a circuit including the rheostat 234 and hence the motor 145 is now in operation. This condition is indicated by lighting of the red signal lamp 235, which is energized by closing of the contacts 6CR3 of relay 6CR, the green signal lamp 236 having been extinguished by the simultaneous opening of contacts 6CR4 of relay 6CR.

It will be apparent, therefore, that by placing the blade 182 of the selector switch at the position marked "Sequence" and momentarily depressing the switch 184, the apparatus will be automatically sequentially energized in the order: stock level indicator and the carriage motor, conveyor 100, conveyor 15, screen means 58, conveyor 136, and conveyor 144. It will be observed that due to the presence of the interlock relays such as 1CR, 2CR, 3CR, 4CR, and 5CR none of the portions of the apparatus may be energized unless the preceding portion of the apparatus has already been placed in operation. The sequential energization is, however, rapidly effected so that the push button switch 184 does not have

to be maintained depressed for an appreciable length of time. This sequential starting insures against any pile up of material within the feeder, or overflow therefrom, since the exit drives for the apparatus are placed in operation before the conveyor 144 which brings the material to the apparatus. Hence, if the conveyor 100 or the screen means 58, for example, should fail to start, the motor 145 for the supply conveyor 144 cannot be energized.

With the circuits completed as just described, the conveyor 144 carries material to the conveyor 136 which in turn delivers the material to the screen means 58. The screen 58 by its shaking action both feeds and screens the material, the undersize particles being removed from the apparatus by the conveyor 15 while the particles equal to or greater than the minimum size are fed forwardly onto the conveyor 100 which, in turn, delivers the material into the furnace or other receptacle in substantially uniform layers therein due to the reciprocation of the carriage 21 which is automatically effected in a manner about to be described. The indicating means, comprising the lamps 202, 203 and the chains 124, continuously indicate whether or not the stock level, that is the upper surface, of the material within the receptacle or furnace, is at the desired uniform height.

Energization of the control circuit and of the several motors in the manner just described results in movement of the carriage 21 in a forward direction, that is, towards the furnace or receptacle 20. The initial energization of control circuit in the manner described always energizes the motor 49 for effecting movement of the carriage in this direction due to the fact that the forward limit switch 50 is normally closed and hence the initial energization of the circuit results in energization of the relays 1F and 2F, thereby closing the contacts 1F3 and 2F1. At the same time the contacts 1CS6 are opened during initial energization, and by the time these contacts close relay 1F has opened its contacts 1F2 thereby preventing the closing of the circuit for energization of the motor 49 in a manner causing reverse rotation thereof. In the normal operation of the apparatus the carriage with the various conveyors and the screen means thereon moves forwardly until the switch operator 52 on the carriage engages and actuates the forward limit switch 50 thereby opening its normally closed contacts. This deenergizes the relays 1F and 2F and also relays 1M and DB. The deenergization of relay 1F opens its contacts 1F1, 1F3 and closes its contacts 1F2, while the deenergization of relay 2F opens its contacts 2F1. Opening of the contacts 1F3 and 2F1 deenergizes the armature of the shuttle carriage motor 49, thus terminating movement of the carriage in the forward direction, this stopping being assisted by the fact that the deenergization of relay DB has closed its contacts DB1, thereby providing a shunt circuit about the armature 49a of the motor 49 to effect dynamic braking thereof. The deenergization of the relay 1M opens its contacts 1M1 thereby further insuring against continued energization of the armature 49a.

When the push button group start switch 184 was released, after initially starting the apparatus, the relays 1CS and 2CS were deenergized. Hence, the contacts 1CS6 are now closed so that the closing of the contacts 1F2 now completes a circuit from the wire 161 through the now closed

contacts 1CR3, 1CS6, contact 237a of a manual switch 237, contact 238a of a manual switch 238, normally closed manual switch 239, to and through the normally closed contacts of the 5 rear limit switch 51 and thence through the normally closed contacts of the overtravel limit switch 54, through the said closed contacts 1F2, to and through the coils of relays 1R and 2R to the power supply line 162. The resulting energization of relay 1R opens its contacts 1R1, thereby preventing inadvertent energization of relays 1F and 2F. Energization of relay 1R also closes its contacts 1R2 in the power circuit for the armature of the motor 49. Energization 10 of the relay 2R closes its normally open contacts 2R1 and 2R2. The closing of the contacts 2R1 completes a circuit therethrough and through the switch 192 reenergizing the relay 1M. Energization of relay 1M again closes contacts 1M2 thereby energizing relay DB as previously described. Consequently the contacts 1M1 are again closed and the contacts DB1 are opened. Opening of the contacts DB1 removes the shunt braking circuit about the armature 49a of the 15 motor 49 while the closing of contacts 1M1 and 1R2 completes the circuit for energization of the armature 49a for rotation in the reverse direction, it being remembered that the contacts 1F3 and 2F1 are open. This reversal of direction 20 of rotation of the motor 49 does not affect the operation of the other motors or of the indicating means and hence the carriage simply reverses its direction of movement, thus moving the carriage of feeding apparatus away from the receptacle 25 or furnace 20, the material being continuously fed thereto as the conveyor 100 moves backwardly over the top surface thereof.

When the carriage 21 has reached a position such that the delivery end of the conveyor 100 is adjacent the right-hand side wall of the receptacle or furnace 20, as viewed in Fig. 1, the switch actuator 53 will engage and operate the rear limit switch 51 opening the latter. This deenergizes the relays 1R and 2R thus opening the contacts 1R2 and 2R2 in the circuit for the armature 49a of the motor 49. Deenergization of relay 2R also deenergizes relay 1M, due to the opening of the contacts 2F1. Deenergization of relay 1M opens its contacts 1M2 thus deenergizing relay DB so that the contacts DB1 are closed. Also, the contacts 1M1 are opened. Hence, electrodynamic braking of the armature is provided and improper energization thereof is prevented.

It will be observed that as soon as the carriage has begun its movement in the rearward direction, the contacts of switch 50 will automatically close since these contacts are normally urged in a closed direction by spring means or the like. 50 Consequently, when the carriage has reached its rearwardmost position, thereby deenergizing the relay 1R, as just mentioned, the resulting closing of the contacts 1R1 again completes the previously described circuit for effecting energization of relays 1F and 2F so that the motor 49 is again energized to rotate in the direction productive of forward motion of the carriage as previously described. As soon as the carriage 60 again begins to move in this forward direction, the actuator 53 will move from engagement with the switch 51 so that the contacts of the latter close under the action of spring means or the like, not shown, with the result that the circuit is again prepared for proper operation of the motor to move the carriage in a rearward

direction after the carriage has reached its forwardmost position as described.

In the event it is desired to completely withdraw the conveyor 103 from the hood of the furnace or receptacle, this can be effected by manually energizing the carriage motor 49 for rotation in a reverse direction even after the rear limit switch 51 has been opened. This is rendered possible through holding push button switch 188 depressed. This opens the circuit for relay 1CR through contact 188a of switch 188 thus releasing the holding circuits for the several motors. As a result the contacts 1CR3 are opened so that the carriage motor 49 is not energized for rotation in a forward direction. Actuation of switch 188 also moves its contact 188b to circuit closing position, thus completing a circuit from wire 161 through a wire 240 to and through contact 188b, through switch 54, contacts 1F2, and relay coils 1R and 2R to the wire 162. The energization of relays 1R and 2R complete the above described circuits for effecting energization of the carriage motor 49 to move the carriage to the rear. This movement continues until the switch actuator 53 engages and operates switch 54 thus opening the contacts thereof and stopping the motor, the switch 54 being so positioned that it is not operated until the carriage has been completely removed from the furnace hood. The carriage may be again moved forwardly by releasing the push button switch 188 and again operating the start switch 184 or switch 199.

In the event that the indicating means such as the lights 202, 233 indicate voids in the top surface of the material during the automatic reciprocation of the carriage, the carriage may be held without movement by depressing the manually operable push button switch 192. This deenergizes the relay 1M and hence relay DB, so that the contacts 1M1 are opened and the contacts DB1 are closed, thereby deenergizing and stopping the armature of the carriage motor 49. The relays 1F and 2F, or 1R and 2R, whichever are energized in accordance with the direction of movement of the carriage before operation of switch 192, are not affected by operation of the push button switch 192. Moreover, the relay 1CR is not deenergized and consequently the carriage will remain stationary as long as the push button 192 is held depressed without interrupting the operation of the several conveyors and of the screen means with the result that material continues to be delivered to the furnace or receptacle without reciprocation of the carriage. When the push button switch 192 is released, the relays 1M and DB are again energized and the carriage will resume its operation in the direction in which it was moving before operation of the switch 192.

In the event the carriage is moving in a forward direction and it is desired to reverse the latter before it reaches its extreme position operating the corresponding limit switch 50, the manually operable push button switch 191 is depressed momentarily. Operation of this switch opens the circuit therethrough thus deenergizing relays 1F, 2F, 1M and 1DB so that the carriage motor 49 is stopped. However, relay 1CR remains energized holding contacts 1CR3 closed and, since relay 1CS was deenergized when the start push button 184 was released, contacts 1CS6 are closed. Therefore, deenergization of the relay 1F closes its contacts 1F2 thereby completing a circuit from the wire 161 through contacts 1CR3, 1CS6, 231a, 238a, 239, 51, 54, 1F2 to and through the relay

coils 1R and 2R energizing these relays. Energization of relays 1R and 2R completes the previously described circuits energizing motor 49 in the reverse direction and the carriage movement is therefore reversed. Since the relay 1CR remains energized, the several conveyors and the screen means remain in operation as the carriage moves rearwardly until the limit switch 51 is actuated effecting automatic return of the carriage or until one of the manual switches 237, 238, or 239 is operated. If none of the switches 237, 238 or 239 be actuated, the carriage moves rearwardly until the actuator 52 thereon engages and operates switch 51 whereupon the switch and relay operations are as above described terminating the rearward movement and initiating the forward movement. The apparatus will then continue in automatic operation under control of the forward and rear limit switches until one of the manual switches is again operated.

In the event the carriage is moving in a rearward direction, that is to the right as viewed in the drawings, and it be desired to reverse the direction of movement of the carriage so as to cause the latter to move in the forward direction before the carriage reaches the position for operation of the limit switch 51, this reversal of direction of motion may be effected by momentarily manually depressing the forward push button switch 239. Operation of this switch opens the circuit for the relays 1R, 2R, 1M and DB so that the carriage motor 49 is stopped. However, relay 1CR remains energized holding contacts 1CR2 closed. Therefore, the closing of contacts 1R1 as the result of deenergization of relay 1R completes a circuit extending from the wire 161 through the contacts 1CR2, wire 190, switches 191, 50, contacts 1R1 to the wire 162 through the coils of the relays 1F and 2F. Energization of the relays 1F and 2F completes the circuits previously mentioned for energizing the relays 1M, DB and completes the circuit through the armature of the motor 49 in a manner effecting rotation of the latter in a direction causing forward motion of the carriage. The carriage will then move in this new direction until the actuator 52 engages and operates switch 50 as above described.

The actuation of either switch 191 or 239 to reverse the movement of the carriage does not interrupt the operation of the various conveyors and the screen means since the control relay 1CR remains energized thus maintaining the circuits for the conveyors and screen means energized through the above described relay contacts. Hence, if the indicating lights 202, 233 evidence that there is a void or voids in the surface of the material in the furnace the carriage may be immediately returned over that portion of the furnace to supply additional material thereto. Since the switch 191 may be actuated at any point in the forward movement of the carriage, and the switch 239 may be actuated at any point in the rearward movement of the carriage, the carriage can be repeatedly moved over a given area in the furnace by alternate operation of these switches and without the necessity of having the carriage operate either limit switch 50 or 51.

The control circuit for the carriage motor is also provided with two manually operable stop switches 185 and 186 of the push button type. Operation of either of these stop buttons will stop the motion of the carriage, regardless of its direction of movement, and also deenergize

the various drive motors for the conveyors and the screen means, since the operation of either the stop buttons 185, 186 breaks the circuit for the relay 1CR. Upon release of the actuated stop switch, the circuits are not restored, since the sequence control relays 1CS, 2CS do not remain energized after their group start button 184 is released. Starting of the apparatus may, however, be again effected by operation of the group start button 184 and the apparatus will resume operation in the manner previously described. The carriage may be independently started, however, by operation of either of its push button type start switches 237, 238, thereby closing a circuit through the upper contacts thereof 237b, 238b, energizing the relay 1CR. It will be observed that operation of either of these start switches 237 or 238 opens the circuit through the lower contacts 237a or 238a, which control the energization of the relays 1R and 2R and hence the carriage will resume movement in a forward direction regardless of its direction of movement prior to stopping.

The indicating means is not deenergized by the previously mentioned stopping or changing the direction of movement of the carriage by operation of the manual switches such as 185, 186, 188, 199, 191, or 239 since the contacts 2M1 provide a holding circuit for relay 2M which is independent of the other relays in the circuit. The indicating means may, however, be deenergized by operation of one or the other of the manual push button stop switches 197 or 198 in the energizing circuit of relay 2M. The indicating means may again be energized by operation of the group start switch 184 or may be started independently of the remaining portions of the apparatus by operation of either of the manually operated start buttons 241 or 242, either of which is effective to close a circuit energizing the relay 2M.

If the carriage has been individually started by operation of either of the manually operable switches 237 or 238, the conveyors and screen means may be individually jogged or may be manually started in their sequential order by sequentially operating the individual start switches associated therewith, that is by operating the start switches 243, 244, 245, 246, and 247 in that sequential order. This follows from the fact that energization of the relay 1CR in the carriage control circuit has closed the contacts 1CR6 so that operation of the manual switch 243, resulting in energization of the relay 2CR and hence closing of the contacts 2CR1, energizes relay 3M controlling operation of the motor 101 and completion of the holding circuit for relay 2CR. Likewise, the energization of relay 2CR closes the contacts 2CR5 so that operation of the switch 244 energizes relay 3CR and, in turn, relay 4M, thus starting the motor 76. Also, energization of relay 3CR closes the contacts 3CR5 so that operation of the switch 245 energizes relay 4CR, and hence relay 5M, starting the motor 72 for the screen means. The energization of the relay 4CR closes the contacts 4CR5 so that operation of the switch 246 now energizes relay 5CR, and hence relay 6M, starting the motor 137. Finally, the energization of relay 5CR closes the contacts 5CR5 thereof so that operation of the switch 247 effects energization of relays 6CR and 7M starting the motor 145.

For safety purposes an additional push button switch, in the control circuit, is mounted near

each individual drive motor. These switches are of the type having a ferrule or collar settable to hold the switch in a partially depressed position. If this collar be set so that the switch is in its "On" position, the several motors operate as previously described. If, however, the collar of a switch be set in "Safe" position, the corresponding switch is partially depressed, as indicated by broken lines in Fig. 14, so that the circuits therethrough are opened and the operation cannot be sequentially effected as previously described. However, each individual motor, except the carriage motor, may then be "jogged" by further depression of the push button switch having such a collar while the collar is in the "Safe" position. Jogging of the carriage motor can be effected, as previously described, by switches other than the safety switch. These safety switches are the switches previously designated and referred to as 187, 214, 219, 224, 228 and 233.

It will be observed that the switch 187, in the carriage motor control circuit, is in the nature of a simple stop switch, provided with a settable collar to hold it in its depressed or "Safe" position, while each of the other switches comprise two sets of contacts, one of which opens a circuit when the other closes a circuit. Thus, the switch 214 in the control circuit of motor 101 has its contact 214a moved to open position when the switch is operated. This contact is maintained in the open position, indicated by broken lines in Fig. 14, when the ferrule or collar is operated and in which position the upper contact 214b does not quite close the circuit through the relay 3M. However, with the switch 214 in its "Safe" position, that is with the contact 214a in its broken line position, the switch 214 may be further depressed, thus moving the contact 214b into circuit closing relationship thereby energizing relay 3M so that the contacts 3M2 are closed thus energizing the motor 101.

It will be observed, however, that, since the contact 214a is in open position when switch 214 is thus actuated, the relay 2CR cannot be energized and hence the next motor in sequence, namely, motor 76, is not prepared for energization. Moreover, the motor 101 does not remain in operation when the switch 214 is released since the contact 214b then moves to open position. This is true whether the contact 214a returns to either its "Safe" position, if the collar remains in its previous position, or to the circuit closing position shown in full lines in the drawing, if the collar has been restored permitting such operation. In other words, operation of the switch 214 can only be used for jogging the motor 101 for operation of that individual motor and that only so long as the switch is manually held depressed. Moreover, since the circuit to the relay 2CR is opened whenever the contact 214a is depressed, each of the other drive motors following the motor 101 in the previously mentioned sequential order, is deenergized whenever the switch 214 is operated. Each of the other switches 219, 224, 228 and 233 likewise has an upper contact 219b, 224b, 228b and 233b, respectively, which operates in conjunction with the lower contact of the corresponding switch to control the individual associated motors 76, 72, 137 and 145, respectively, in the same manner as described for the motor 101.

With the selector switch 182 positioned to engage the terminal marked "Manual" any drive in the apparatus may be started or stopped indi-

ividually at the discretion of the operator. This mode of operation is intended primarily only for setup purposes or for taking care of unexpected contingencies in the operation of the apparatus or of the mechanisms with which it is used. It will be observed that when the switch 182 is thus placed in the manual position, a circuit is completed from the wire 161 through the said switch to and through relays 1CM and 2CM to the wire 162. The resulting energization of the relay 1CM closes its contacts 1CM1, 1CM2, 1CM3, and 1CM4, while energization of the relay 2CM closes its contacts 2CM1. With the circuits thus established, it will be observed that operation of the sequence control switch 184 is now ineffectual and that each of the various elements of the apparatus must be individually started by operation of its individual start switch.

Thus, the carriage motor 49 may now be energized by operation of either of the start switches 237 or 238 thereby energizing the relay 1CR which closes its contacts 1CR1 providing a holding circuit around the start switches, the relay 1CR also operating the other contacts thereof to effect energization of the motor 49 as will be apparent from the previous description. It will be observed that the motor 49, thus energized, will continue in operation until manually stopped by operation of one or the other of the switches such as 185 or 186. Although energization of relay 1CR closes the contacts 1CR3 in the control circuit for the motor 101, the latter is not energized by operation of either of the start switches for the motor 49 since the contacts 1CS2 are open. Likewise, none of the other drive motors is energized.

The motor 101 may, however, be started by depressing its start switch 243. This energizes its relay 2CR thereby closing the contacts 2CR1 and hence completing the circuit through these latter contacts and the now closed contacts 1CM1 to and through the relay 3M energizing the latter. A holding circuit is provided by the closing of the contacts 2CR2 and 3M1 and energization of the relay 3M also causes closing of its contacts 3M2 thereby starting the motor 101. It will be observed that the motor 101 may thus be started whether or not the carriage motor 49 is energized.

The motor 76 may be started in a similar manner by depressing the start switch 244. Likewise, the motors 72, 137 and 145 may be individually started by depressing the corresponding start switches 245, 246, and 247, respectively. It will be observed that starting or stopping of any of these motors when switch 182 is in the "Manual" position has no effect upon the operation of the other motors and that each must be individually manually stopped.

The various signal lamps and the manually operable switches utilized in normal operation of the apparatus are conveniently grouped in two control panels illustrated in Figs. 11 and 12. Preferably the control panel 248, illustrated in Fig. 11, is the main control panel and is located at a convenient position with respect to the carriage or other operating parts of the apparatus associated therewith. Upon this control panel 248 are provided the red indicator lamps 263 for the stock level indicating means, and adjacent these lamps are start switch 242 and stop switch 188 controlling the energization of the indicating means as well as the signal lights 216 and 217 which disclose the operating condition of the indicating means. The shuttle carriage control switches such as start switch 239, stop switch 186, forward switch 190, reverse switch 193, and the signal lights 206, 208 are also mounted adjacent

each other upon the panel 248. The control panel 248 is further provided with the selector switch 182 and the group start switch 184. Panel 248 is additionally provided with the start switch 243, 5 stop switch 213, and signal lights 216, 217 for the conveyor 100, a hand wheel 249 also being provided thereon for controlling rheostat 215 of the motor 101. Also, the start switch 244, stop switch 218, and signal lights 221, 222 for the conveyor 75 together with a hand wheel 250 for controlling the rheostat 220 for the motor 76 of this conveyor are mounted on the panel 248. In addition the panel 248 has start switch 246, stop switch 228, signal lights 230, 231 for the conveyor 136, hand wheel 251 being provided adjacent these control switches for regulating the rheostat 229 of the motor 137 for that conveyor. Likewise, panel 248 is provided with the start switch 247, stop switch 232, signal lights 235 and 236 for conveyor 144, 20 a hand wheel 252 for adjusting the rheostat 234 of the motor 145 for that conveyor being mounted on the panel adjacent these switches and lights. Finally, the start switch 245, stop switch 223, and signal lights 225, 226 for the screen means 58 are also provided on the control panel 248.

The auxiliary control panel, generally designated 253 and illustrated in Fig. 12, is preferably located adjacent the receptacle or furnace 20 being charged and, in this instance, is preferably mounted upon a side of a hood 254 for the furnace adjacent the opening through which the conveyor 100 extends. This control panel 253 is provided with the indicator lights 262 of the stock level indicating means, the start switch 241, stop switch 197, and signal lights 209, 211 for the indicating means. Also upon the panel 253 are the start switch 237, stop switch 185, and signal lights 205, 207 for the control circuit of the carriage motor 49 as well as a hand wheel 255 for adjusting the rheostat 196 of that motor. In addition, the panel 253 is provided with the reversing switches 188, 191 and the hold switch 192 for the motor 49.

It will be apparent therefore that the operator can control the movement of the carriage and the energization of the stock level indicating means while directly observing the operation of the conveyor 100 from a position adjacent the furnace, or other receptacle, as well as from a point remote therefrom, such as at the main control panel 248. 45 The previously mentioned switches 187, 214, 219, 224, 228 and 233 are preferably mounted adjacent each of the motors controlled thereby since they are intended primarily for safety purposes and not for normal operation of the apparatus. 50 The several disconnect switches, such as 160, 166, 170, 171, 172, 173, 174, 175, 176, 177, 178, 179, 180 and 181, are provided for the purpose of isolating various portions of the circuit to facilitate repairs thereon and in certain instances may be omitted, if desired. These switches may be located where convenient. As mentioned heretofore, conventional safety devices such as fuses, current overload switches and the like have been omitted from the illustration of the circuit for purposes of simplicity.

In summary, it will be observed that with the switch 182 set in the position indicating "Sequence," operation of the group start switch 184 will simultaneously energize the stock level indicating means and the carriage motor, whereupon the motors for the conveyors 100, 75, screen means 58, and conveyors 136 and 144 will next be energized in that order, the sequential energization being so rapid as to appear substantially

simultaneous with the energization of the carriage motor. However, if the carriage motor or any of the other drive motors should fail to be energized this will prevent energization of all the other drive motors following the non-operating motor in the sequential order.

When these circuits for the various drive motors have been established by operation of switch 184, the material is delivered from a source of supply by means of the conveyor 144 to the conveyor 136 which in turn delivers the material to screen 58. The material passing over the screen is delivered to the conveyor 100 and is charged by the latter into the furnace or receptacle 20, the undersize material which passes through the screen being removed by the conveyor 75. The delivery of the material to the receptacle is normally effected by continuous reciprocation of the delivery end of the conveyor 100 over the top of the furnace or receptacle due to the reciprocating movement of the carriage 21, the direction of movement of the latter being automatically reversed at positions corresponding with positions of the delivery end of the conveyor 100 adjacent opposite side walls of the furnace 20 or other receptacle being charged. During this movement, the stock level indicating means continuously indicates whether or not the top surface or stock level of the material within the receptacle or furnace is at a uniform predetermined height.

In the event one or more of the indicating lamps such as 202, 203 is extinguished, this indicates that a void is present in the stock level or surface of the material in the receptacle 20 at the region then being traversed by the chain 124 corresponding with the extinguished indicating lamp. If this void is not corrected by the automatic operation of the carriage, the latter may be held at a given position in its reciprocation without interrupting the delivery of the material by manually operating the hold push button 192. Correction for voids may also be effected by reversing the direction of movement of the carriage at any point in its cycle of reciprocation, by operating the proper reversing switch 191 or 239, without terminating delivery of the material.

It will be further observed that in the event one portion of the mechanism should stop or be stopped for any reason, each of the succeeding drive motors of the apparatus in the sequential order of starting will be stopped automatically. This prevents piling up of the material either within the furnace, or other receptacle being charged, or upon the feeding apparatus. Thus, if the conveyor 100 should stop or be stopped for any reason, the conveyors 75, 136 and 144 would likewise stop, as would the screen means 58, so that no more material would be supplied to the feeding apparatus nor would the material then present in the apparatus be delivered to the furnace. Likewise, if the screen means 58 or the conveyor 75 which removes the undersize particles from the apparatus, should stop or be stopped, the conveyors 144 and 136 supplying additional material would likewise stop. Stopping of the carriage, other than by operation of switch 192, will stop each of the conveyors and the screen means. Provision is also made in the machine for manual operation of each of the separate portions thereof.

It will thus be seen that the apparatus of this invention effects feeding of discrete bodies of material to a receptacle, such as a shaft furnace or the like, in a manner providing a substantially uniform stock line or top surface of the material

within the receptacle. This feeding is effected in a manner such that any voids occurring in the stock line or top surface of the material in the receptacle charged may be immediately indicated and corrected, a feature which is of paramount importance where the receptacle charged is in the form of a shaft furnace or the like from which material is withdrawn adjacent the bottom and in which it is desired that a uniform bed or stock of material be maintained so that uniform heating will occur therethrough. Furthermore, the apparatus provides for the said feeding operations to be effected with a minimum of breaking stresses upon the bodies of the material, provision also being made for automatically removing bodies smaller than a predetermined minimum size, thereby insuring that the bodies charged to the furnace or other receptacle are of a size equal to or greater than a predetermined minimum.

While the apparatus has been described in considerable detail with respect to use in charging a shaft furnace, rectangular in cross-section, it will be apparent that the apparatus may also be employed for charging bins or other receptacles where similar problems are involved. Furthermore, modifications and variations in the construction of the apparatus may be effected by those skilled in the art without departing from the inventive concept here disclosed. Therefore the illustrations and descriptions are intended only for the purposes of disclosing a practical embodiment of the invention in its present preferred form and are not to be construed as limitations thereon.

Having thus described the invention, we claim:

1. An apparatus of the character described for use in charging material in the form of discrete bodies into a receptacle, the said apparatus comprising a vibratile screen means the openings of which are such as to permit passage therethrough of the bodies of the material having a size less than a predetermined size, conveyor means for delivering material from a source of supply to said screen means in a substantially uniform stream, means supporting said screen means adjacent the rear thereof in a manner permitting adjustment of the horizontal and vertical components of the vibratory motion imparted to the bodies of the material thereon, conveyor means having a substantially planar surface extending substantially horizontally with a portion adjacent the discharge of said screen means to receive the material passing thereover, and means connected with the last-mentioned conveyor means for effecting reciprocating movement of the delivery end thereof over the top of the receptacle, whereby only bodies of material having a size greater than a predetermined minimum are charged into said receptacle and said charged material is distributed substantially uniformly throughout the cross-sectional area of the receptacle.

2. An apparatus as defined in claim 1 where-in the said screen means and the said last-mentioned conveyor means extend in the same direction and the width of said screen means adjacent its point of discharge to the said last-mentioned conveyor means is substantially equal to the width of the latter so that the bodies of material are delivered to said last-mentioned conveyor means and from the latter to said receptacle with a substantially uniform transverse distribution.

3. An apparatus of the character described for use in charging material in the form of dis-

crete bodies into a receptacle with a substantially uniform distribution of the material throughout the cross-sectional area of the receptacle, the said apparatus comprising a carriage movably mounted adjacent the top of said receptacle, motion producing means operatively connected to said carriage for effecting reciprocation thereof relative to the top of said receptacle, screen means carried by said carriage, means delivering material to said screen means in a substantially uniform stream, conveyor means having a substantially planar surface extending substantially horizontally with a portion adjacent the discharge of said screen means to receive the material passing thereover, and means connecting said last-mentioned conveyor means with said carriage for reciprocating movement of the delivery end of said last-mentioned conveyor means over the top of said receptacle in response to movement of said carriage, whereby only bodies of the material having a size greater than a predetermined minimum are charged into said receptacle and the said charged material is disposed substantially uniformly throughout the cross-sectional area of the receptacle.

4. An apparatus of the character described for use in charging material in the form of discrete bodies into a receptacle with a substantially uniform distribution of the material throughout the cross-sectional area of the receptacle, the said apparatus comprising a carriage movably mounted adjacent the top of said receptacle, motion producing means operatively connected to said carriage for effecting reciprocation thereof relative to the top of said receptacle, screen means carried by said carriage, power means supported on said carriage and operatively connected to said screen means for shaking the latter, means delivering material to said screen means in a substantially uniform stream, conveyor means having a substantially planar surface extending substantially horizontally with a portion adjacent the discharge of said screen means to receive the material passing thereover, and means connecting said last-mentioned conveyor means with said carriage for reciprocating movement of the delivery end of said last-mentioned conveyor means over the top of said receptacle in response to movement of said carriage, whereby only bodies of the material having a size greater than a predetermined minimum are charged into said receptacle and the said charged material is disposed substantially uniformly throughout the cross-sectional area of the receptacle.

5. An apparatus of the character described for use in charging material in the form of discrete bodies into a receptacle with a substantially uniform distribution of the material throughout the cross-sectional area of the receptacle, the said apparatus comprising a carriage movably mounted adjacent the top of said receptacle, motion producing means operatively connected to said carriage for effecting reciprocation thereof relative to the top of said receptacle, screen means carried by said carriage, means delivering material to said screen means in a substantially uniform stream, conveyor means beneath said screen means for removing material passing therethrough, conveyor means having a substantially planar surface extending substantially horizontally with a portion adjacent the discharge of said screen means to receive the material passing thereover, and means adjacent the material receiving end of said last-mentioned conveyor

means connecting the latter with said carriage for reciprocating movement of the delivery end of said last-mentioned conveyor means over the top of said receptacle in response to movement of said carriage, whereby only bodies of the material having a size greater than a predetermined minimum are charged into said receptacle and the said charged material is disposed substantially uniformly throughout the cross-sectional area of the receptacle.

6. An apparatus as defined in claim 5 and wherein the width of said last-mentioned conveyor means is substantially equal to the transverse dimension of the interior of the receptacle being charged, the direction of reciprocation of said last-mentioned conveyor being at right angles to said transverse dimension with the length of reciprocatory stroke being substantially equal to the internal dimension of said receptacle in the direction of said reciprocatory movement.

7. An apparatus as defined in claim 5 wherein the said screen means and said last-mentioned conveyor means extend in the same direction and the width of said screen means adjacent its point of discharge to said last-mentioned conveyor means is substantially equal to the width of the latter so that the bodies of material are delivered to said last-mentioned conveyor means in a manner providing a substantially uniform transverse distribution thereon.

8. An apparatus of the character described for use in charging material in the form of discrete bodies into a receptacle with a substantially uniform distribution of the material throughout the cross-sectional area of the receptacle, the said apparatus comprising a carriage supported for movement adjacent the top of said receptacle, power means supported upon said carriage and operatively connected thereto to produce reciprocation of said carriage relative to the top of said receptacle, screen means carried by said carriage, means delivering material to said screen means in a substantially uniform stream, means beneath said screen means for removing material passing therethrough, power actuated conveyor means having a substantially planar surface extending substantially horizontally with a portion adjacent the discharge of said screen means to receive the material passing thereover, and means connecting said power actuated conveyor means with said carriage for reciprocating movement of the delivery end of said power actuated conveyor means over the top of said receptacle in response to movement of said carriage, whereby only bodies of the material having a size greater than a predetermined minimum are charged into said receptacle and the said charged material is disposed substantially uniformly throughout the cross-sectional area of the receptacle.

9. An apparatus as defined in claim 8 and wherein the said power means on said carriage for producing reciprocating movement of the latter comprises a reversible electric motor, and electrical switch means connected in the energizing circuit for said motor and actuated by movement of said carriage to predetermined positions thereof to effect reversal of the direction of rotation of said motor whereby said carriage is automatically continuously reciprocated.

10. An apparatus as defined in claim 8 and wherein the said power means on said carriage for effecting reciprocating movement of the latter comprises a reversible electric motor, electric switch means connected in the energizing circuit

for said motor and actuated by movement of said carriage to predetermined positions thereof to effect reversal of the direction of rotation of said motor whereby the said carriage is automatically continuously reciprocated, and manually operable switch means connected in the energizing circuit for said motor and adapted to be selectively actuated to effect reversal or stopping of said motor independent of the position of said carriage.

11. An apparatus of the character described for use in charging material in the form of discrete bodies into a receptacle with a substantially uniform distribution of the material throughout the cross-sectional area of the receptacle, the said apparatus comprising a carriage movably mounted adjacent the top of said receptacle, motion producing means operatively connected to said carriage for effecting reciprocation thereof relative to the top of said receptacle, screen means carried by said carriage, power means supported on said carriage and operatively connected to said screen means for shaking the latter, means delivering material to said screen means in a substantially uniform stream, conveyor means beneath said screen means for removing material passing therethrough, conveyor means having a substantially planar surface extending substantially horizontally with a portion adjacent the discharge of said screen means to receive the material passing thereover, means adjacent the said material receiving portion of said last-mentioned conveyor means connecting the latter with said carriage for reciprocating movement of the delivery end of said last-mentioned conveyor means over the top of said receptacle in response to movement of said carriage, and means adjacent the said delivery end of the last-mentioned conveyor means movably supporting the latter on opposite sides of said receptacle, whereby only bodies of the material having a size greater than a predetermined minimum are charged into said receptacle and the said charged material is disposed substantially uniformly throughout the cross-sectional area of the receptacle.

12. An apparatus of the character described for use in charging material in the form of discrete bodies into a rectangular receptacle with a substantially uniform distribution of the material throughout the cross-sectional area of the receptacle, the said apparatus comprising a wheeled carriage supported for movement adjacent the top of the receptacle to be charged, a vibratile screen supported upon said carriage, a conveyor supported upon said carriage with its delivery end adjacent one end of said screen, the said conveyor having a substantially planar surface so that the material is delivered thereby to said screen in a substantially uniform stream, a second conveyor connected to move with said carriage and having a substantially planar surface extending substantially horizontally with a portion positioned to receive material from the other end of said screen and deliver the material to said receptacle in a substantially uniform stream, means for delivering material to said first conveyor, means continuously removing from the carriage any material passing through said screen, and means for imparting reciprocatory movement to said carriage thereby moving the delivery end of said second conveyor transversely of said receptacle.

13. An apparatus as defined in claim 12 and wherein the width of said second conveyor is substantially equal to one transverse dimension

of the interior of said receptacle and the direction of reciprocation of said carriage is at right angles to the said one transverse dimension with the length of reciprocatory stroke being substantially equal to the other transverse dimension of the interior of said receptacle.

14. An apparatus as defined in claim 12 wherein the said means for imparting reciprocatory movements to said carriage includes a reversible electrical motor supported on said carriage and operatively connected to at least one of the wheels thereof, and electrical switch means actuated by movement of said carriage to predetermined positions thereof for reversing the direction of rotation of said motor.

15. An apparatus as defined in claim 12 and wherein the said first and second conveyors and the said means for removing material passing through the screen are each endless belts driven by separate electric motors supported upon said carriage, and means including an electric motor supported on said carriage for vibrating said screen.

16. An apparatus as defined in claim 12 and wherein the said second conveyor projects forwardly from said carriage and is supported adjacent its delivery end by wheels running on rails at either side of said receptacle adjacent the top thereof.

17. An apparatus of the character described for charging material into a receptacle substantially throughout the cross-sectional area of the receptacle, the said apparatus comprising an endless power driven conveyor, means supporting said conveyor for reciprocating movement substantially horizontally over the top of the receptacle to be charged, a reversible electric motor operatively connected with said supporting means to effect reciprocation of the delivery end of said conveyor over the top of the receptacle, a control circuit for said motor including electrical switch means for controlling the direction of rotation of said motor, means moving with said conveyor for operating said switch means at the extremes of reciprocating movement of the conveyor to reverse the direction of movement thereof, means delivering material to said conveyor throughout its reciprocating movement, and operator-actuated switch means in said circuit selectively operable at any point in the cycle of reciprocation of said conveyor to stop or reverse said motor and thereby vary the said cycle of reciprocation to effect filling of voids in the top surface of the material in said receptacle.

18. An apparatus of the character described for charging material into a receptacle with a substantially uniform distribution of the material throughout the cross-sectional area of the receptacle, the said apparatus comprising a conveyor, means supporting said conveyor for movement adjacent the top of the receptacle to be charged, motion producing means operatively connected with the said supporting means to effect automatic reciprocation of the delivery end of said conveyor over the top of the receptacle, means delivering material to said conveyor throughout its reciprocating movement, indicating means including a portion reciprocated with said conveyor transversely of said receptacle adjacent the top thereof and adapted to detect the upper surface of the material in said receptacle, and operator-actuated means selectively operable at any point in the cycle of reciprocation of said conveyor to vary the said cycle of reciprocation of said supporting means without interrupting

the delivery of material to said conveyor to thereby effect the filling of voids in the top surface of the material in said receptacle as detected by said indicating means.

19. An apparatus of the character described for charging material into a receptacle with a substantially uniform distribution of the material throughout the cross-sectional area of the receptacle, the said apparatus comprising a conveyor supported for movement adjacent the top of the receptacle to be charged, motion producing means operatively connected with the said conveyor to produce automatic reciprocation of the delivery end of said conveyor over the top of the receptacle, means delivering material to said conveyor throughout its reciprocating movement, feeler means extending into said receptacle a predetermined distance from the top thereof, signal means actuated by engagement of said feeler means with the upper surface of material in said receptacle, and operator-actuated means selectively operable at any point in the cycle of reciprocation of said conveyor to vary the cycle of reciprocation of said conveyor to effect filling of voids in the top surface of the material in said receptacle as indicated by said signal means.

20. An apparatus of the character described for charging material into a receptacle with a substantially uniform distribution of the material throughout the cross-sectional area of the receptacle, the said apparatus comprising a conveyor supported for movement adjacent the top of the receptacle to be charged, motion producing means operatively connected with the said conveyor to produce automatic reciprocation of the delivery end of said conveyor over the top of said receptacle, means delivering material to said conveyor throughout its reciprocating movement, a plurality of feeler means extending into the top of said receptacle and reciprocated with said conveyor transversely of said receptacle, signal means connected with said feeler means and actuated by engagement of said feeler means with the upper surface of material in said receptacle, and operator-actuated means selectively operable at any point in the cycle of reciprocation of said conveyor to vary the cycle of reciprocation of said conveyor to effect filling of voids in the top surface of the material in said receptacle as indicated by said signal means.

21. An apparatus as defined in claim 20 and wherein the said signal means includes a separate signal lamp operatively associated with each of said feeler means.

22. An apparatus of the character described for charging material into a receptacle with a substantially uniform distribution of the material throughout the cross-sectional area of the receptacle, the said apparatus comprising a carriage movably mounted adjacent the top of the receptacle to be charged, power means operatively connected to said carriage for producing automatic reciprocation thereof relative to the top of said receptacle, a power driven conveyor connected to said carriage for reciprocation therewith in a manner such that its delivery end is reciprocated over the top of said receptacle by movement of said carriage, means delivering material to said conveyor throughout its reciprocating movement, power means actuating said conveyor to cause the latter to deliver the material fed thereto over the delivery end thereof, indicating means including a portion supported by said conveyor for reciprocation therewith trans-

versely of said receptacle adjacent the top thereof, the said indicating means including a portion adapted to detect the upper surface of the material in said receptacle, and operator-actuated means selectively operable at any point in the cycle of reciprocation of said carriage to vary the reciprocating cycle of the latter thereby facilitating filling of voids in the top surface of the material in said receptacle as detected by said indicating means.

23. An apparatus of the character described for charging material into a receptacle with a substantially uniform distribution of the material throughout the cross-sectional area of the receptacle, the said apparatus comprising a carriage supported for movement adjacent the top of the receptacle to be charged, power means supported upon said carriage and operable to produce automatic reciprocation of the latter relative to the top of said receptacle, a power driven conveyor connected to said carriage for reciprocation therewith with its delivery end reciprocating over the top of said receptacle by movement of said carriage, means delivering material to said conveyor throughout its reciprocating movement, power means actuating said conveyor to cause the latter to deliver the material fed thereto over the delivery end thereof, indicating means including a portion supported by said conveyor and reciprocated therewith transversely of said receptacle adjacent the top thereof, the said indicating means including a portion extending into the top of said receptacle to detect the upper surface of the material therein, and operator-actuated means selectively operable at any point in the cycle of reciprocation of said carriage to selectively reverse or interrupt the movement of the latter thereby facilitating the filling of voids in the top surface of the material in said receptacle as detected by said indicating means.

24. An apparatus of the character described for use in charging material in the form of discrete bodies into a receptacle with a substantially uniform distribution of the material throughout the cross-sectional area of the receptacle, the said apparatus comprising a carriage movably mounted adjacent the top of said receptacle, motion producing means operatively connected to said carriage for effecting reciprocation thereof relative to the top of said receptacle, screen means carried by said carriage, means delivering material to said screen means in a substantially uniform stream, conveyor means having a substantially planar surface extending substantially horizontally with a portion adjacent the discharge of said screen means to receive the material passing thereover, means connecting said conveyor means with said carriage for reciprocating movement of the delivery end of said conveyor means over the top of said receptacle in response to movement of said carriage, indicating means including a portion reciprocable with said conveyor means transversely of said receptacle adjacent the top thereof and adapted to detect the upper surface of the material in said receptacle, and operator-actuated means selectively operable at any point in the cycle of reciprocation of said carriage to selectively reverse or interrupt the movement of the latter, thereby facilitating the filling of voids in the top surface of the material in said receptacle as detected by said indicating means.

25. An apparatus of the character described for use in charging material in the form of dis-

crete bodies into a receptacle with a substantially uniform distribution of the material throughout the cross-sectional area of the receptacle, the said apparatus comprising a carriage movably mounted adjacent the top of said receptacle, power operated motion producing means operatively connected to said carriage for effecting reciprocation thereof relative to the top of said receptacle, power operated screen means mounted upon said carriage, power operated conveyor means having a substantially planar surface delivering material to said screen means in a substantially uniform stream, power operated conveyor means supported upon said carriage beneath said screen means for removing material passing therethrough, power operated conveyor means having a substantially planar surface extending substantially horizontally with a portion adjacent the discharge of said screen means to receive the material passing thereover, means adjacent the material receiving end of said last-mentioned conveyor means connecting the latter with said carriage for reciprocating movement of the delivery end of said last-mentioned conveyor means over the top of said receptacle in response to movement of said carriage, and an electrical control circuit including manually operable start and stop switch means and electrical relays operative to effect starting of said power means in sequential order upon operation of said start switch means and stopping of said power means in said sequential order upon operation of said stop switch means so that material cannot pile up on said carriage.

26. An apparatus as defined in claim 25 wherein separate electric motors provide the power for operating each of said power operated means and the said control circuit further comprises separate manually operable start and stop switch means individually operable to individually control the energization of each of said motors, and means in said circuit selectively operable to prepare said circuit for individual manual control of the starting and stopping of said motors or for automatic sequential control thereof.

27. An apparatus of the character described for use in charging material in the form of discrete bodies into a receptacle with a substantially uniform distribution of the material throughout the cross-sectional area of the receptacle, the said apparatus comprising a carriage movably mounted adjacent the top of said receptacle, a reversible electrical motor operatively connected to said carriage for effecting reciprocation of the latter relative to the top of said receptacle, screen means supported upon said carriage, means including an electric motor for shaking said screen, a first power operated conveyor having a substantially planar surface and positioned to deliver material to said screen means in a substantially uniform stream, a second power operated conveyor supported upon said carriage beneath said screen means for removing material passing therethrough, a third power operated

conveyor having a substantially planar surface extending substantially horizontally with a portion adjacent the discharge of said screen means to receive the material passing over said screen means, means connecting said third conveyor with said carriage for reciprocating movement of the delivery end of said third conveyor over the top of said receptacle in response to movement of said carriage, separate electric motors operatively connected to each of said conveyors to effect operation thereof, electrical switch means controlling the energization of said motors in a predetermined sequential order, and other electrical switch means actuated by movement of said carriage to predetermined positions thereof to effect reversal of said reversible motor.

28. An apparatus as defined in claim 27 and further comprising manually-operable switch means for effecting reversal of said reversible motor independently of the position of said carriage.

29. An apparatus as defined in claim 27 and further comprising manually-operable switch means for deenergizing said reversible motor thereby stopping said carriage without interrupting the energization of the other motors.

30. An apparatus as defined in claim 27 and wherein electrical relay means control the sequential energization of the said motors for said third conveyor, said second conveyor, said screen vibrating means, and said first conveyor in that order whereby deenergization of any motor in said order deenergizes all the other motors succeeding the initially deenergized motor in said sequential order.

31. An apparatus as defined in claim 27 and further comprising indicating means including a portion reciprocated with said third conveyor transversely of said receptacle adjacent the top thereof and adapted to detect the upper surface of the material in said receptacle, and manually-operable switch means adapted to control the energization of said reversible motor independently of the position of said carriage to thereby facilitate filling of voids in the top surface of the material in said receptacle as detected by said indicating means.

JOSEPH E. DUNASKY.
